SHOE PRESS

John O. Yunker, Wauwatosa, Wis.

Application July 15, 1933, Serial No. 680,580

12 Claims.

(Cl. 12—33)

This invention relates generally to improvements in the art of attaching soles to footwear, and relates more specifically to improvements in the construction and operation of apparatus for cementing soles to shoes or the like.

5 A general object of the invention is to provide improved apparatus for attaching soles to footwear, which is simple and compact in construction, readily manipulable, and highly efficient in operation.

10 It has heretofore been proposed as in my co-pending application Serial No. 569,388, filed October 17, 1931, and in my Patent No. 1,943,356, granted January 16, 1934, to cement soles into intimate contact with footwear by causing the soles to rest upon resilient pads formed of rubber, and by forcing the footwear toward the soles with the aid of adjustable screws coating with pressure blocks and lasts disposed within the shoes. The reaction pads used in these prior 15 devices were of the pneumatic type containing air chambers completely enclosed within the rubber, and it was also proposed to apply heat within the shoes being soled, in order to augment the adhesive action of the cement. While these prior 20 devices are relatively satisfactory and have met with extensive commercial success, the reaction pads are rather difficult to manufacture and are therefore quite costly; and it is also quite impossible in attaching the soles to certain kinds 25 of relatively thin and flexible footwear, to insure effective attachment of the rear portions of the soles.

It is therefore a more specific object of the present invention to provide improved apparatus for overcoming these objectionable features of the prior devices of this general type.

Another specific object of the invention is to provide an improved resilient reaction pad structure for shoe sole presses, which is simple and durable in construction, and which is moreover 30 relatively effective in use.

A further specific object of the invention is to provide improved instrumentalities for insuring effective attachment of all portions of the soles to all parts of the footwear with which the soles 35 coat.

An additional specific object of the invention is to provide an improved adjustable last especially adapted for use in conjunction with shoe sole presses or the like.

Still another specific object of the invention is to provide an improved pressure block structure for shoe sole presses or the like, and means for heating a last coating with the block.

Another specific object of the invention is to

provide an improved combination last and pressure block for sole attaching machines, which will enable more effective cementing of soles to various types of footwear.

A further object of the invention is to provide various improvements in the details of construction of shoe sole attaching presses, whereby the manufacture thereof is simplified, while the efficiency is enhanced to a maximum.

These and other objects and advantages will be apparent from the following detailed description.

A clear conception of embodiments of the several features of this invention, and of the mode of constructing and of utilizing shoe soling presses built in accordance with the improvement, may be had by referring to the drawing accompanying and forming a part of this specification in which like reference characters designate the same or similar parts in the various views:

Fig. 1 is a part sectional front elevation of one of the improved shoe sole cementing presses;

Fig. 2 is a longitudinal vertical section through one of the reaction pads and through the corresponding metal portions of the press;

Fig. 3 is a top view of the improved press;

Fig. 4 is a fragmentary longitudinal vertical section through a portion of the improved press, showing a modified form of reaction pad;

Fig. 5 is an enlarged top view of one of the improved metal lasts; and

Fig. 6 is a similarly enlarged part sectional side view of the improved combination last and pressure block.

While the invention has been shown and described herein as being specifically applied to a portable duplex unit especially adapted for use in repairing shoes or other footwear, it will be apparent that some of the features are more generally applicable to other types of presses for originally attaching the soles. It should also be remembered that some of the novel features of 40 shoe sole press construction, shown and perhaps described but not specifically claimed herein, form the subject of the two copending applications specifically identified hereinabove.

The improved duplex shoe sole attaching machine illustrated in Figs. 1, 2 and 3, comprises generally a base 8 rotatably mounted upon a standard 9 and having a yoke 10 rigidly attached to the top thereof; a pair of resilient reaction pads 11 detachably supported in recesses formed in the top of the base 8; a pair of vertical screw threaded spindles 12 adjustably associated with hubs formed upon the yoke 10 above the pads 11; one or more pressure blocks 13 having detents 45 cooperable directly with the pointed lower ends

of the spindles 12; and one or more metallic lasts 14 formed for cooperation with the lower portions of the pressure blocks 13 and with the upper interiors of the sole portions of the shoe 15 being repaired.

The base 8 may be formed of cast iron or aluminum, and is rotatably attached to screw threads at the upper end of the standard 9 which may be formed of a suitable length of pipe having a 10 relatively large and heavy base plate 16 permanently secured to the lower end thereof. The yoke 10 may likewise be formed of cast iron or aluminum and is rigidly bolted to the base 8 rearwardly of the pivotal axis, as shown in Fig. 3, 15 and the pad confining recesses in the top of the base 8 are bounded by vertical side walls 17 and concave bottoms 18 as shown in Figs. 1 and 2, and the rear side walls 17 are provided with depressions 19 for accommodating the heels of footwear 20 being soled.

The resilient reaction pads 11 specifically shown in Figs. 1, 2 and 3, are each constructed of a heavy upper and side bearing portion 20 of firm but flexible rubber, and a lower inner core 21 of 25 relatively softer highly resilient material such as sponge rubber. The sides of the heavy bearing portion 20 of each pad 11, coact directly with the side walls 17 and with the edge portions of the concave bottom 18 of the corresponding pad confining recess, and the core 21 may be formed of 30 any desired thickness and reacts against the central portion of the concave bottom 18 thus providing considerable cushioning effect. The pads 11 may be readily inserted within or removed 35 from their confining recesses within the base 8, but snugly fit these recesses after insertion thereof. The rear depressions 19 are not of sufficient extent to prevent such snug confinement of the pads 11, and as previously indicated, these depressions merely provide proper heel clearances.

The pressing spindles 12 are movable toward and away from the pads 11 with the aid of a handle 22, only one of which need be provided, and which is detachably cooperable with the flattened upper ends 23 of the spindles 12, and the handle 22 may be provided with a weight 24 for facilitating spinning of the spindle 12 with which the handle is associated. As previously indicated, the lower spindle points are cooperable with any 45 one of a series of detents 25 formed in the upper arm of the pressure block 13, and the detent 25 actually selected for such cooperation depends upon the size and style of shoe 15 being operated upon. The lower arm of the pressure block 13 50 may engage the upper inclined surface of the last 14 either directly, or indirectly through an electric heater 26, depending upon whether or not it is desired to apply heat in order to hasten the cementing operation. The heater 26 may be loosely applied or permanently attached to the lower arm 55 of the block 13, and is provided with a safety cut-out device 27 for preventing over-heating.

The pressure block 13 may be formed of any suitable metal, and besides having the heater 26 attached thereto, if used, this block has an integral rear projection 28 which is threaded for the reception of an adjustable rod 29. The upper end of the rod 29 is provided with a manipulating hand wheel 30, and the lower end thereof 60 carries a universally movable pressure plate 31. The plate 31 is adapted to coact with the rear swingable section 32 of the last 14, and this section 32 is pivotally attached to the forward main section by means of a pin 33 so that the section 65 32 may be readily adjusted by moving the rod

29 either while the block 13 and last 14 are within or outside of the shoe 15. The last 14 and its movable section 32 may be formed of aluminum or the like, and the main section of this last may either be formed solid or ribbed, and has relatively inclined lugs 34 at the forward end thereof for preventing the pressure block 13 from sliding forwardly over the end of the last.

When the improved press has been properly assembled as shown in Figs. 1, 2 and 3, the device 10 may be utilized to quickly and effectively attach soles to footwear, in the following manner. The sole and the surface of the shoe 15 to which it is to be attached, may first be properly prepared, after which adhesive such as liquid cement may 15 be applied and the shoe 15 and sole positioned with the sole in contact with the top of the pad 11 and the corresponding spindle 12 in coaction with a pressure block 13 and last 14 cooperat- 20 ing with the interior of the shoe 15. The handle 22 may then be manipulated to force the pressure block 13 and the last 14 downwardly against the sole, whereupon the resilient pad 11 coacting with the outer sole will be distorted as shown, 25 by virtue of the sponge rubber core 21 coact- 25 ing with the concave bottom 18 of the pad con- 30 fining recess. This distortion of the pad 11 will cause pressure to be uniformly applied to the outer sole throughout the entire forward por- 35 tion thereof, and in order to also insure proper 40 application of pressure to the rear portion of the sole, the hand wheel 30 may be utilized. By turning this hand wheel 30, the threaded rod 29 will be moved downwardly, causing the plate 31 to 45 force the hinged last section 32 against the in- 50 terior shank and heel portions of the shoe 15. The shank and heel portions may thus be forced into intimate contact with the rear portion of 55 the pad 11 to insure thorough cementing of the rear part of the sole, and the depression 19 will 60 accommodate the heel of the shoe during this operation. If so desired, the heater 26 may be em- 65 ployed to hasten the cementing operation, and the safety device 27 will prevent overheating and possible scorching.

While the pad construction shown in Figs. 1, 2 and 3 has been found to be a satisfactory substitute for the hydraulic and pneumatic pads previously used, a pad 11' such as shown in Fig. 4 may also be utilized. The pad 11' merely com- 50 prises a relatively heavy body 20' of compara- 55 tively stiff but flexible rubber having an open space 21' in the under side thereof. The side walls of this pad 11' are adapted to snugly en- 60 gage the side walls 17 of the corresponding pad 65 confining recess in the base 8, and rest upon the edge portions of the concave bottom 18 so that when the pad 11' is in place, the space 21' is sub- 70 stantially sealed. When pressure is applied to this modified pad 11', the confined air within the space 21' acts as an internal cushion and coop- 75 erates with the rubber body 20' to effectively ap- 80 ply and distribute the upward pressure acting upon the outer sole of the shoe 15, and the ad- 85 justable hinged last 14 may also be utilized with considerable advantage in conjunction with this type of pad.

From the foregoing description it will be ap- 90 parent that the present invention provides im- 95 proved pad structures which may be readily utilized in substitution for the more expensive and less durable hydraulic and pneumatic pres- 100 sure pads heretofore used, to produce effective cementing of the soles. The improved adjustable last and pressure block, may be caused to cooper- 105 110

ate with the resilient reaction pads, to insure proper application of pressure at the rear portions of the soles, and the adjustment of the hinged last section may obviously be effected 5 either before or after the shoe 15 has been applied to the press proper. Since the pressure block 13 is formed entirely independent of the last structure, and merely rests loosely upon the upper surface of the last, it is preferable to force 10 the hinged last section 32 against the heel portion of the shoe 15 after the shoe, last, and pressure block have been assembled in the press, whereupon the hand wheel 30 may be adjusted to produce any desired degree of additional pressure 15 upon the heel portion of the shoe independently of the pressure being applied through the main last 14. The straight upright side wall 17 and the concave bottom 18 cooperate to insure most effective and uniform distribution of 20 the pressure regardless of the type of reaction pad which is used, and the improved pads may be utilized in machines built originally for the reception of standard pneumatic pads.

It should be understood that it is not desired 25 to limit the invention to the exact details of construction and to the precise mode of operation herein shown and described, for various modifications within the scope of the claims may occur to persons skilled in the art.

30 It is claimed and desired to secure by Letters Patent:

1. In combination, means for applying resilient pressure to an outer sole coacting with a shoe along a cement coated surface, a last coacting 35 with the interior of the shoe and having a section movable toward the shank portion of the shoe, a pressure block coacting with said last, and adjustable means carried by said block and cooperable with said movable last section to force 40 the latter against the shank portion of the shoe independently of the pressure applied through said block.

2. In combination, means for applying resilient pressure to an outer sole coacting with a shoe along a cement coated surface, a last having 45 a main section cooperable with the interior sole portion of the shoe and having a pivotally mounted section swingable toward and away from the shank portion of the shoe, a pressure block coacting 50 with said main last section, and adjustable means carried by said block for swinging said pivoted section relative to the shank of the shoe.

3. In combination, a resilient reaction pad, a last cooperable with a shoe resting upon said pad, said last having a section movable directly toward 55 and against the shank of the shoe independently of the remainder of the last, and adjustable means for moving said section relative to the remainder of the last while the latter is in pressing engagement with a shoe.

60 4. In combination, a resilient reaction pad, a last insertable within a shoe resting upon said pad, said last having a pivoted section swingable toward the shank of the shoe independently of the remainder of the last, and adjustable means manipulable while the last is in pressing engagement with a shoe to swing said pivoted section 65 toward the shank of the shoe.

5. In combination, a resilient reaction pad, a last cooperable with a shoe resting upon said pad and having a section swingable toward the shank of the shoe, and a pressure block coacting with said last and having means for swinging said section.

6. In combination, a resilient reaction pad, a last cooperable directly with the inner wall of a shoe resting upon said pad and having a pivoted rear section swingable toward the shank of the 10 shoe, a pressure block coacting with said last and having a rearwardly extending portion, and adjustable means carried by said rearwardly extending portion and cooperating with said swingable last section. 15

7. In combination, means for applying downward pressure against the inner sole of a shoe, and a resilient pad cooperable with the outer sole of the shoe, said pad comprising an outer casing having a top and side walls of relatively stiff flexible rubber and a core of sponge rubber confined within said walls and disposed beneath said top. 20

8. In combination, means for applying downward pressure upon the inner wall of a shoe, an elastic pad cooperating with the outer sole of 25 the shoe, and pivotally supported means movable relative to said pressure applying means and toward the shank portion of the shoe while said pressure applying means is effective. 30

9. In combination, a base having a recess provided with a central concave bottom, a resilient pad confined within said recess and coacting with said bottom, a last coacting with a shoe resting upon the central portion of said pad, and means for forcing a portion of said last into intimate 35 engagement with the shank of the shoe to force said shank toward the adjacent portion of said pad. 40

10. In combination, a base having an inclined surface, a resilient pad resting against said surface and having an upper surface above said inclined base surface cooperable with the rear of the outer sole of a shoe, a last cooperable with the interior of the shoe and having a section movable toward said base surface, means for moving said section, and independent means for forcing said last toward the shoe. 45

11. In combination, a base having an inclined surface, a resilient pad resting against said surface and having an upper surface above said inclined base surface cooperable with the rear of the outer sole of a shoe, a last cooperable with the interior of the shoe and having a pivoted section movable toward said base surface, means for swinging said section relative to said last and 50 against the shank of the shoe, and means for forcing said last and said section toward the shoe. 55

12. In combination, means for applying pressure downwardly upon a shoe, and a pad for coacting with the outer sole of the shoe, said pad comprising an outer casing having a top and side walls formed of relatively stiff material and having a cushion portion confined within said walls and disposed below said casing top, and a frame coacting with said casing walls and with said cushion portion to provide an elastic cushion. 60 65
